2 Sheets-Sheet 2

UNITED STATES PATENT OFFICE.

DONALD S. MCCHESNEY, OF SYRACUSE, NEW YORK, ASSIGNOR TO HALL & MCCHESNEY INC., OF SYRACUSE, NEW YORK, A CORPORATION OF NEW YORK.

LOOSE-LEAF BOOK.

Application filed March 4, 1927. Serial No. 172,622.

This invention relates to a new and improved loose leaf book.

The main object of the invention is the production of an improved loose leaf book, the parts of which are so shaped, connected and arranged as to permit a more ready, easy and efficient operation of the book in use and in the removal and insertion of leaves, and in which the book is more effectively maintained from distortion and changes in shape and form, and whereby a more permanent and lasting structure is provided in which the covers are freely movable with respect to the housings which carry the leaf supporting posts.

Other objects and advantages relate to the details of the structure and the form and relation of the parts thereof, all as will more fully appear from the following description taken in connection with the accompanying drawings, in which:

Figure 1 is a perspective view of a portion of a loose leaf book of this invention illustrating the posts separated from one of the housings, but connected with the other.

Figure 2 is a perspective view of the same book showing the posts secured to both housings.

Figure 3 is a lateral cross-section through the book.

Figure 4 is a similar section showing the book opened.

Figure 5 is a section on line 5—5, Figure 3.

Figure 6 is a plain view of the slide.

Figures 7, 8 and 9 are perspective views of different forms of posts.

The loose leaf book as here illustrated comprises two covers —1— and —2— which may be faced by a binding strip —3— of leather, canvas or the like, and which extends over all or a portion of the surface of the covers and around the rear of the book. In addition a second binding strip —4— is provided which may be bound into the covers —1— and —2—, the latter being formed of cardboard or the like, and this strip —4— also extends around the rear end of the book and may be separated from the strip —3— at the rear end of the book by means of a binder board —5—.

The covers —1— and —2— may be formed of layers of cardboard or the like secured together between which layers the ends of the strips —4— are secured. In addition each of

the covers —1— and —2— carries a plate —8— preferably of metal or the like which extends rearwardly from the covers when the latter are in closed position. Preferably these plates each comprise two thicknesses of sheet metal and each is formed from a single strip of sheet metal return bent upon itself and provided with an end portion extending at an angle to the body of the strip and formed with spaced barrels —6— for the reception of a pivot rod —7—. These strips, as illustrated, extend into the respective covers —1— and —2—, and are secured in position by rivets —10—. The two strips —3— and —4— between the rear ends of the covers —1— and —2— and the opposite ends of the binder board —5— are in contact with each other, and are secured together and to the respective plates in any suitable manner, as by an adhesive so as to form hinged portions adjacent the opposite ends of the binder board —5—.

A back plate —11— is provided preferably formed of a flat sheet of metal and with which the rear ends of leaves secured in the book are adapted to contact. At its opposite edges the back plate —11— is formed with spaced barrels —12— mounted upon the pivot rods —7—.

For the purpose of removably carrying the leaf supporting posts there are provided two housings —14— and —15— in the form of rectangular tubes and having at their rear ends spaced barrels —16— and —17— respectively mounted upon the pivot rods —7—.

It will be apparent that the plates —8— with their respective covers —1— and —2—, the back-plate —11— and the housings —14— and —15— are all pivotally supported with respect to each other upon the pivot rods —7—. Each housing is formed with a plurality of transverse aligned openings in its opposite walls for the reception of the posts —13—. In this illustration five posts are shown, and each of the housings is formed with five sets of aligned openings. The inner openings —27— in the housings when the book is closed are of an area approximately the size of the posts —13— and of substantially the same shape, while the outer openings —22— are smaller and are tapered to receive the tapered ends —18— of the posts, and for the purpose of holding the posts rigidly in position with respect to the housings

there are provided similarly shaped slides —19— of a width substantially the same as the interior width of the housings, but of a thickness substantially less than the thickness of the housings, as for instance substantially half the thickness, and these slides are formed with pintles —20— raised from one surface and adapted to move through openings —21— in the opposite ends of the posts.

10 The complete thickness of the slides —19— and raised pintles —20— is substantially equal to the interior width of the housings —14— and —15— and the reduced ends of the posts —13— are held tightly in the comparatively small tapered openings in the outer sides of the housings.

It will be apparent that the plates —8— are in effect portions of the two covers respectively in that the plates are rigid extensions of the covers and move with the covers, and for the purpose of the claims of this application, these plates may be deemed portions of the covers for effecting a pivotal connection of the cover to the back plate and to 25 the tubular housing.

Each of the slides —19— is preferably provided with a hook portion —60— adapted to form a grip for moving the slides.

30 The posts —13— may be of various forms so long as they are provided with tapered ends —18—, and in Figure 7 a post of generally rectangular cross-section is shown, while in Figure 8 a post generally square in cross-section is shown, and in Figure 9 a post generally circular in cross-section is shown.

For the purpose of receiving the tapered ends —18— of the posts, the plates —8— are provided with openings —61— aligned with the ends of the posts when the latter are inserted in the housings, and of a size adapted to substantially fit the ends of the posts.

Altho I have illustrated and described a specific structure as constituting a perhaps preferred embodiment of this invention, I 45 do not desire to restrict myself to the details of the structure or the particular form and relation of the parts thereof, as various changes and modifications may be made within the scope of the appended claims.

50 I claim:

1. A loose leaf book comprising a back plate, covers hinged to the back plate, a tubular housing hinged to each cover and to the back plate, each housing provided with a pair of aligned openings, the openings in the inner sides of the housing being larger than the openings in the outer sides of the housings, and a post having its opposite ends tapered, said post extending through the openings in the inner sides of the housings and having its tapered ends fitted in the smaller openings in the outer sides of the housings, and means for holding the posts in their position.

65 2. A loose leaf book comprising a back

plate, covers hinged to the back plate, a tubular housing hinged to each cover and to the back plate, each housing provided with a pair of aligned openings, the openings in the inner sides of the housing being larger than the openings in the outer sides of the housings, and a post having its opposite ends tapered, said post extending through the openings in the inner sides of the housings and having its tapered ends fitted in the smaller openings in the outer sides of the housings and slides movable in the housings and engaging the post to maintain it in position.

3. A loose leaf book comprising a back plate, covers hinged to the back plate, a tubular housing hinged to each cover and to the back plate, each housing provided with a pair of aligned openings, the openings in the inner sides of the housing being larger than the openings in the outer sides of the housings, and a post having its opposite ends tapered, said post having openings through its opposite end portions and slides in the housings having pintles extending through said openings to maintain the posts in position.

4. A loose leaf book comprising a back plate, covers hinged to the back plate, a tubular housing hinged to each cover and to the back plate, each housing provided with a pair of aligned openings, the openings in the inner sides of the housing being larger than the openings in the outer sides of the housings, and a post having its opposite ends tapered, said post extending through the openings in the inner sides of the housings and having its tapered ends fitted in the smaller openings in the outer sides of the housings, means for holding the posts in their position, and a binding having hinged connections with the two covers and extending across the back plate.

5. A loose leaf book comprising a back plate, covers hinged to the back plate, a tubular housing hinged to each cover and to the back plate, each housing provided with a pair of aligned openings, the openings in the inner sides of the housing being larger than the openings in the outer sides of the housings, a post having its opposite ends tapered, said post extending through the openings in the inner sides of the housings and having its tapered ends fitted in the smaller openings in the outer sides of the housings, slides movable in the housings and engaging the post to maintain it in position, and a binding having hinged connections with the two covers and extending across the back plate.

6. A loose leaf book comprising a back plate, covers hinged to the back plate, a tubular housing hinged to each cover and to the back plate, each housing provided with a pair of aligned openings, the openings in the inner sides of the housing being larger than the openings in the outer sides of the housings, a post having its opposite ends ta-

pered, said post having openings through its opposite end portions and slides in the housings having pintles extending through said openings to maintain the posts in position, 5 and a binding having hinged connections with the two covers and extending across the back plate.

7. A loose leaf book comprising a tubular housing having aligned openings in its outer 10 and inner sides, the opening in the inner side being larger than the opening in the outer side and a post extending through the opening in the inner side of the housings and having a tapered end fitted in the smaller opening 15 in the outer side of the housing and means for maintaining the post in position.

8. A loose leaf book comprising a tubular housing having aligned openings in its outer 20 and inner sides, the opening in the inner side being larger than the opening in the outer side and a post extending through the opening in the inner side of the housings and having a tapered end fitted in the smaller opening 25 in the outer side of the housings, and a slide member engaging the post to maintain it in position.

9. A loose leaf book comprising a tubular housing having aligned openings in its outer 30 and inner sides, the opening in the inner side being larger than the opening in the outer side and a post extending through the opening in the inner side of the housings and having a tapered end fitted in the smaller opening 35 in the outer side of the housings, and a slide member of less width than the width of the housing and adapted to slide within the housing and having a raised pintle engaging the post to maintain it in position.

10. A loose leaf book comprising a back

plate, covers hinged to the back plate, a tubular housing hinged to each edge of the back plate, a series of aligned openings in each housing similarly disposed, posts having ends adapted to fit into opposed openings in said housings and join the same together, and a 45 slide in each housing having a series of off-set pintles adapted to engage holes in said posts, said holes being spaced from the ends of said posts.

11. A loose leaf book comprising a back 50 member, a cover member hinged to the back member, a tubular housing hingedly mounted on one of said members for swinging movement with respect to both the back member and the cover member, said housing provided 55 with a pair of aligned openings, the opening in the inner side of the housing being larger than the opening in the outer side of the housing, a post having a tapered end, said post extending through the opening in the 60 inner side of the housing and having its tapered end fitted in the smaller opening in the outer side of the housing, and means for holding the post in position.

12. A loose leaf book comprising a back 65 plate, covers hinged to the back plate, a tubular housing hinged to each edge of the back plate, a series of aligned openings in each housing similarly disposed, posts having ends adapted to enter opposed openings in said 70 housings to join the same together, a slide in each housing having slots for receiving the ends of the posts, and offset pintles on the slides adapted to engage holes in the posts.

In witness whereof I have hereunto set my 75 hand this 19 day of February, 1927.

DONALD S. McCHESNEY.
